UNITED STATES PATENT OFFICE.

TRUMAN A. WOOD AND WILLIAM T. WOOD, OF WICHITA, KANSAS.

HOISTING AND STRAW-CONVEYING MACHINE.

Application filed August 2, 1921. Serial No. 489,299.

To all whom it may concern:

Be it known that we, TRUMAN A. Wood and WILLIAM T. Wood, citizens of the United States, residing at Wichita, in the county 5 of Sedgwick and State of Kansas, have invented certain new and useful Improvements in a Hoisting and Straw-Conveying Machine, of which the following is a description, referring to the drawings which accompany this specification.

The invention relates particularly to a hoisting machine, adaptable for combination as an independent unit with vehicular supports, such as wagons, trucks, separators and 15 the like; or on stationary supports; in the construction illustrated the machine is shown in combination with a threshing machine with the ordinary hay fork operated by the hoist depositing wheat or other grain straw 20 upon the conveyor for threshing operations. It will be understood, however, that devices other than the hay fork are employed for handling other commodities or materials. Other and specific improvements will be designated in the description of the drawings, 25 in which, Fig. 1 represents a plan view of the machine. Fig. 2 is a side elevation of Fig. 1 looking in the direction of the arrow. Fig. 3 is a front elevation of Fig. 1. Fig. 4 is a side view of a brake element in combination with and for locking a cable reeling drum, shown in section. Fig. 5 is a top view 30 of Fig. 4. Fig. 6 is a perspective view of the lever operating means controlling clutch engagement intermediate the driving shaft and a cable reeling drum. Fig. 7 is a perspective view of the lever operating means for engaging and reversing the action of the friction beveled drive mechanism for swinging 35 the boom. Fig. 8 is a sectional view taken through the slideable driven shaft of a friction bevel driving mechanism, along the line 8—8, Fig. 3 looking in the direction of the arrow. Fig. 9 is a view taken along the 40 line 9—9, Fig. 8. Similar numerals of reference indicate corresponding parts throughout all the figures of the drawings.

Referring to the drawings, the base framing elements 11 of the machine may be 50 mounted on any suitable supporting surface or platform 12, which may be embodied in a support such as the separator 13 having a conveyor 14. The drive wheel 15 of the machine may be driven by a belt 16 driven from an engine, motor, or other power developing 55 means.

The wheel 15 is loose on the main shaft 17 of the machine. The shaft 17 is mounted in the bearings 18, 18 on the frame 11. A small sprocket wheel 19 rigid with the wheel 15, 60 drives a sprocket chain 20 leading around the larger sprocket wheel 21 fixedly fastened to the shaft 22 mounted in a bearing 23 on the frame 11. A smaller sprocket wheel 24 rigid with the shaft 22 carries a chain 25 65 driving a larger sprocket rigid with the shaft 17 for power and speed reduction purposes. The shaft 17 furnishes power for driving twin sets of mechanism operable, each independent of the other, for the purposes of the invention and arranged at opposite ends of the machine as illustrated in Figs. 1 and 4. A chain 26 driven from a sprocket rigid with the shaft 17 intermediate the twin sets of mechanism drives a 70 sprocket rigid with the shaft 27 which is mounted in bearings 28, 28 on the frame 11 also intermediate said twin sets and functional in common with either of said sets independent of the other.

A description of the mechanism shown at the left of Fig. 3 next follows, it being understood that the twin set at the right thereof functions in a similar manner. A cable reeling drum 29 is loosely mounted on the 85 shaft 17. A cone clutch 30 slidably mounted on a keyway (not shown) on the shaft 17 is engageable or disengageable with a functioning clutch face on said drum 29 for reeling the cable 31. A lever handle 32 rigid 90 with a shaft 33 supported in bearings 34, 34 on the frame 11 operates the forked crank 35 rigid with the shaft 33. The crank 35 engages a pin 36 rigid with a rocker shaft 37 mounted in bearings 38 in the frame 11 95 and carrying a forked arm 39 engaging in the ring slot of the clutch 30. By moving the handle 32 forward or back as indicated by its dotted arc movement Fig. 1 the clutch 30 engages with or disengages from the 100 drum 29. The vertical mast 40 is rotatably arranged and supported in bearings carried by members 41, 42 supported from the frame 11. A boom 43 pivotally mounted at 44 to a collar rigid with the mast 40 is secured also 105 by the cable 45 at a desired inclination to the mast.

When the clutch 30 engages the drum 29, the cable 31 carried by the boom 43 is reeled up to raise the hayfork 46 and straw or other 110 load carried by the cable 31, to a desired height, when the clutch is released and a

lever 47 pivoted at 48 on the frame 11 is simultaneously drawn rearwardly as indicated by the arrow Fig. 4 and whereby the brake band 49, connecting by members 50, 51 to the lever 47 is tightened on the drum 29 to maintain the load at the desired reeled position.

It is now desirable to rotate the boom through the arc indicated in Fig. 1 to deposit the load from the member 46 on the conveyor 14 or other dump. The shaft 52 mounted in bearings 53 in the frame 11 carries a crank 54 rigid therewith. A forked shifting lever 55 connects pivotally at 56 with the crank 54 by means of the rod 57. The forks of the lever 55 engage a grooved collar 58 rigid with a shaft 59 rotatably and slidably mounted endwise in the outer bearing 60. The inner end of the shaft 59 is squared as at 61 to slidably engage for endwise movement with the square hole or seat axially aligned in the outer end of the driven shaft 27.

Pressing on the foot pedal 62 rigid with the shaft 52 operates to move the lever 55, the collar 58 and the shaft 59 to the right, Fig. 3 and from the neutral position there indicated the truncated conical friction drum 63 would then engage the beveled periphery of the friction wheel 64 rigidly mounted on the base of the mast 40 and whereby rotation of the shaft 27 would transmit arc rotation of the boom 43 in one direction; similarly pressing down on the foot pedal 65 would operate to move the companion friction drum 66 to engage the wheel 64 for boom 43 rotation in the opposite direction. The set at the right of Fig. 3 as stated operates in a similar manner and

both sets may operate at the same time if desired. The mechanism described is both simple in operation and efficient and available for a wide application. Such modifications may be employed as lie within the scope of the appended claim.

Having fully described our invention what we now claim as new and desire to secure by Letters Patent is:

In a machine of the class described, a frame, a main driven shaft arranged in bearings therein, an auxiliary shaft in parallelism therewith and in bearings in the frame, square holes axially aligned in the opposite ends of said shaft, central driving means operatively engaging intermediate said shafts; twin sets of hoisting mechanism arranged one set on either side of said central driving means, each set comprising a cable reeling drum loosely mounted on the main shaft, a clutch and clutch means for engaging said drum to the main shaft and brake means cooperating with the drum; a vertical mast rotatable in said frame, a boom pivotally supported from the mast, a cable carried by the boom engaging the drum; a shiftable shaft in bearings in the frame and having a square end portion slidably mounted within the adjacent square hole of the auxiliary shaft; a beveled friction driving mechanism intermediate and in combination with said mast and shiftable shaft and means for transmitting desired endwise movement to said shiftable shaft.
